CLAIM

The ornamental design for a bottled water dispenser insert, as shown and described.

DESCRIPTION

FIG. 1 is a top perspective view of a bottled water dispenser insert showing my new design;

FIG. 2 is a top plan view thereof;

FIG. 3 is a side elevation view thereof;

FIG. 4 is a bottom plan view thereof; and

FIG. 5 is a cross-section view thereof, taken along line 5—5 of FIG. 2.

*Fig. 2**Fig. 1**Fig. 3**Fig. 4**Fig. 5*
